UNITED STATES PATENT OFFICE.

DAVID MORLEY HEY, OF CHATTANOOGA, TENNESSEE, ASSIGNOR TO VACUUM DYEING MACHINE COMPANY, OF CHATTANOOGA, TENNESSEE, A CORPORATION OF TENNESSEE.

DYEING APPARATUS.

1,172,240.

Specification of Letters Patent. Patented Feb. 15, 1916.

Application filed April 5, 1910. Serial No. 553,469.

To all whom it may concern:

Be it known that I, DAVID M. HEY, a citizen of the United States, residing at Chattanooga, in the county of Hamilton and State of Tennessee, have invented new and useful Improvements in Dyeing Apparatus, of which the following is a specification.

This invention relates to dyeing apparatus of the circulatory type and particularly to the means thereof for heating the dye liquor.

Dyeing apparatus of the general type to which the present invention relates may be divided generally into two different styles. In one of these styles of apparatus heretofore known the dyeing chamber proper comprises a tank in which the material being dyed is held under compression between perforated top and bottom plates, and the dye liquor after passing through the material and the upper plate overflows entirely around the top of the dyeing chamber into an overflow chamber, which is formed by an outer tank of greater diameter and greater depth than the dyeing chamber, extending above and entirely surrounding the dyeing chamber. This overflow chamber is provided at one side with a suction opening, provided with an emission pipe which is connected with the suction side of a centrifugal pump. This pump acts to withdraw liquor from the overflow chamber and to return it to the dyeing chamber, the liquor entering the latter through the perforated bottom thereof. The overflow chamber has provision, usually in the form of a steam pipe coiled around the dyeing chamber, for heating the liquor. In the other style of these apparatuses of the prior art there is substituted for the outer tank of the style first referred to an overflow chamber which is arranged at the side of the dyeing chamber but does not extend entirely around the same. This overflow chamber has communication with the dyeing chamber at one side only of the center of the latter through an outlet formed in the wall common to the dyeing chamber and the overflow chamber. In this style the provision for heating the dye liquor has been afforded by steam pipes arranged below the bottom perforated plate of the dyeing chamber. These two styles may be arbitrarily designated as a "double tank" and "single tank" form, respectively. Practical experience with these embodiments

has disclosed that delicacy and uniformity of coloring has not been secured and they are wholly unadapted for cold vat dyeing. I have learned that these disadvantages are due to the practical impossibility of securing an even distribution of heat throughout the mass of dye liquor and the maintenance of the liquor at a particular predetermined temperature, and at the same time a uniformly distributed flow of liquor through the materials in such a manner as to avoid formation of channels. The careful regulation of both these conditions, namely, the temperature of the treating liquor and the presentation of equal amounts of liquor to all parts of the material being treated, is essential to attain the best results.

One of the objects of the present invention is to provide an apparatus by means of which both of these conditions may be accurately controlled and regulated.

In the double tank type of apparatus above referred to, since the heating pipe is coiled around the dye chamber, a greater heat is imparted to the liquor in the portions of the overflow chamber remote from the suction opening than is given to the liquor within the area of effective suction. This induces a tendency of this, more highly heated, liquor to rise and to interfere with the free overflow of the liquor from the contiguous portion of the dyeing. Again, the tendency is to unequally heat the dye chamber. Thus, the action in these devices is to make it practically impossible to maintain the dyeing chamber at a uniform temperature, to compel a uniform flow of dye liquor through all parts thereof, and to maintain the liquor itself at a predetermined temperature. With the single tank form, some of these disadvantages have been reduced, but other effects contributing to a non-uniform dyeing and the impracticability of securing of delicate colors have been noted. Thus, while the overflow chamber is of such size that its entire area may be under effective suction, yet its location at one side only of the dyeing chamber, induces an uneven flow of liquor within the latter. Again, it has been noted that the steam collects near the bottom of the vat and effects a back pressure within the dye-liquor supply pipes or jets up through the dye-liquor along the sides of the vat. Moreover, in this type, as in the other, there is no op-

portunity to determine the heat of the dye liquor previous to its admission to the dyeing chamber, and in both of these types the dyeing chamber is variably heated by radiation from the steam pipes, the portions thereof adjacent to the latter being more highly heated than the portions remote therefrom.

The ultimate object of my present invention is to provide a dyeing apparatus which will overcome these disadvantages and be fully capable of producing uniform and delicate colorings throughout the entire mass of material and be capable of use with cold-vat dyes. In pursuance of this ultimate object I have provided a dyeing apparatus having various new and severally useful features whereby (a) any desired temperature of the dye-liquor may be maintained, (b) the entire mass of material may be uniformly treated, (c) there will be no tendency of the steam to collect near the bottom of the vat or to effect a back pressure within the supply pipe or to jet up through the dye-liquor along the sides of the dyeing chamber or vat, and (d) the apparatus will be fully adaptable for cold vat dyeing.

These several purposes are well secured by the construction illustrated in the accompanying drawings, exemplifying what I regard to be the best form of my present invention, but to the details of which the invention is not restricted, as will hereinafter appear.

In these drawings:—Figure 1 is a side elevation of the preferred form of my apparatus, with a portion of the dye vat broken away to disclose elements therein. Fig. 2 is a plan view of the preferred form of heater. Fig. 3 is a vertical section on the line 3—3 of Fig. 2.

Similar characters of reference designate corresponding parts in the several views.

In the accompanying drawings I have exemplified my invention in what is now regarded as the best form thereof and in connection with a dyeing apparatus of the "single tank" type, and I shall particularly describe this exemplification thereof, but it is to be understood that the invention in its broader aspects is not restricted thereto.

A designates a dyeing vat of suitable shape, circular or otherwise, size and construction and, as already stated, of the single tank form. This vat is, as usual, provided with a suitable perforated bottom plate 1 and a suitable perforated top plate 2. The bottom plate 1 is preferably arranged, as usual, above the bottom of the vat sufficiently to provide a space 3 for the incoming liquor, or for the means which supply the dye liquor to the dyeing chamber 4. This dyeing chamber is shown as formed by said perforated top and bottom plates 65 and the side wall or walls of the vat A. The

top plate 2 is adjustable to compress the material between it and the bottom plate, and is held in its adjusted position, preferably by the clamping devices 6 which have been hitherto employed for such purpose.

It will be understood that the dye liquor is introduced under pressure into the space 3 below the bottom plate 1 and thence flows through said plate, the dyeing chamber and the top plate, and overflows from the space 70 above the latter and is again returned to the space 3 for a repetition of its stated course of travel, which is kept up until the material to be dyed has been sufficiently treated. This flow of the liquor is accomplished, as is usual, in the circulatory type 75 of dyeing apparatus, by a suitable centrifugal pump B whose pressure side has connection with the inlet space 3 and whose suction side has connection with the portion of 80 the dye vat A arranged above the perforated top plate 2. These connections include what I call a heating or mixing tank or receptacle. The hereinafter described association of the described heating or mixing tank with the dyeing vat and pump, in substantially the arrangement shown has advantages in respect to the heating of the liquor to a predetermined temperature, and its introduction into the dyeing chamber at 85 substantially a uniform temperature, and its freedom from liability of communicating substantially varying temperature to the mass of material contained in the dyeing chamber; and, therefore, is preferred, but 90 the invention in its broader aspects is not restricted thereto, as already stated.

The heating or mixing tank or receptacle C, is preferably open at the top and is shown as provided with a plurality of inter- 105 communicating chambers, as 10 and 11, preferably formed by one or more division walls or baffle plates 12 which are interposed between the inlet to and outlet from the tank and terminate above the bottom of the lat- 110 ter. The chamber 10 preferably has communication with the portion of the dye vat on the discharge side of the perforated top plate 2, by a return pipe 13 which serves for the inlet of the liquor thereto, and the chamber 11 preferably has communication with the suction opening of the pump, through suitable pipes, as 14, 15 and 16. The inlet end of the pipe 14 is preferably ex- 115 tended downward into the chamber 11 as 120 shown in Fig. 3. Suitably disposed in said tank is a heating element, the one shown being formed of a coiled pipe 17 for steam or other suitable heating fluid, having apertures 17° for the emission of the heating 125 fluid. The preferred location of this heating element is at the bottom of the tank below the baffle plate or division wall 12 and it preferably extends throughout the length of the opening through which the 130

two chambers have communication with each other. As here illustrated, the heating tank is arranged to receive gravitally the overflow from the dye vat via the peripheral overflow chamber or trough.

It will be apparent that in the illustrated embodiment the tank C is under suction which acts to draw the liquor therethrough, said liquor entering through the pipe 13 and leaving by way of the pipe 14, and that the baffle plate or division wall restricts the diameter of the tank or mixing receptacle and forces the liquor to travel in a circuitous path to the outlet in a stream so related to the heating element arranged in its path that it will be uniformly heated and will uniformly take up the heating fluid emitted therefrom, the arrangement being such that the degree of heat imparted to the liquor issuing therefrom is readily determinable with sufficient accuracy to answer the requirements of cold vat dyeing, (i. e. dyeing with liquor of a temperature substantially less than the boiling point) or the imparting of delicate and uniform coloring to the material under treatment.

As already stated, the dyeing liquor is returned to the dyeing chamber. In the illustrated embodiment this return is by way of the outlet b from the pump, and the pipes 18, 19 and 20, in the order named. In the space 3 of the vat A means for the egress of the heated dye liquor are provided. This may be of any suitable kind, such, for example, as those now employed or the one illustrated in my application filed of even date herewith: and numbered, serially, 553,470.

In the exemplified form of my invention, provision is made for the reversal of the flow of the liquor, when desired. This preferably consists of the pipe 21 extending from the junction of suction or return pipes 15 and 16 to the junction of pressure or supply pipes 18 and 19, and pipes 22, 23 and 24 leading from the junction of the pipe 18 with the pump outlet b to the junction of suction pipes 14 and 15. It will be understood that suitable valves are arranged in the couplings 25, 26, 27, 28 and 29, operable to cause the liquor to flow in either direction; that is to say, from outlet b, through pipes 18, 19 and 20 to the dyeing chamber, and through pipe 13, heating chamber, pipes 14, 15 and 16 back to pump, or to flow from the pump outlet b, to the upper part of the dyeing chamber, through pipes 22, 23, 24, 14, heating chamber and pipe 13, and back to the suction side of the pump through pipes 20, 19, 21 and 16. This reversal is not essential to my invention. It will be noted, however, that when the flow is thus reversed the heating chamber is on the pressure side of the pump instead of the suction side thereof. In fact, it may be stated that while I prefer to arrange the

heating chamber between the dyeing chamber and the suction side of the pump, and outside of the dyeing vat, as important advantages are secured thereby, yet, it may be otherwise disposed without departing from the spirit of the invention considered in its broader aspects.

In practice, with the arrangement illustrated it is preferred to heat the liquor in the heating chamber to a slightly higher temperature than is required in dyeing, to allow for loss of heat in its travel to the dyeing chamber, and also to interpose a supplemental heating device, as the steam nozzle 30 in the path of the liquor to the dyeing chamber. This steam nozzle 30 preferably extends to and opens into the steam pipe 17. A valve 31 is preferably provided to cut off the pipe 30 when it is seen that the supplemental heat supplied therethrough is unnecessary.

It is preferred to connect the pipe 13 to an overflow chamber. I greatly prefer to employ as such overflow chamber one, D, which extends entirely around the upper part of the vat A, has a continuous outlet 40 from the latter, at a place arranged above the perforated plate 2, and is formed to provide a comparatively shallow and narrow conduit or trough 41 inclined to the pipe 13. The dye liquor thus can overflow entirely around the upper end of the dye vat and be regularly conducted to the pipe 13 situated at the lowest place in the inclined conduit or trough.

It will be apparent, among other things, that the open space between the heating tank and the dyeing chamber constitutes one way by which the heating device is insulated from the dyeing chamber, whereby the temperature of the latter is not substantially affected by the heating means, as it is in the previous devices embodying pipes coiled around the heating chamber, or arranged contiguous thereto, with no provision for preventing radiation from the heating device to the dyeing chamber.

It is to be understood that while I have herein set forth my invention as a dyeing apparatus, it may be used as a bleaching apparatus, and this and other analogous uses of the apparatus are contemplated to be within the spirit of the invention and the scope of the subjoined claims.

Having now described the invention what I believe to be new and desire to secure by Letters Patent, is:—

1. In a dyeing apparatus, the combination with a dye vat, of a pump, a connection between the pump and the dye vat at the inlet side of the dyeing chamber, a connection between the pump and the dye vat at the outlet side of the dyeing chamber, and a heating tank interposed in the latter connection, said tank being divided longitudinally by a

depending baffle into communicating chambers and provided with a heating element arranged below said baffle.

2. In a dyeing apparatus, the combination with a dye vat, a pump, a connection between the pump and the dye vat at the inlet side of the dyeing chamber, a connection between the pump and the dye vat at the outlet side of the dyeing chamber, a heating tank having a plurality of compartments connected by a passage extending longitudinally of said tank and a heating element adjacent to such passage, said heating tank being arranged in the connection between the outlet side of the dyeing chamber and the pump, and a supplemental heating element in the connection between the pump and the inlet side of the dyeing chamber.

3. In a dyeing apparatus, a vat having a treating chamber, a heating chamber arranged outside said vat and adapted to receive overflow therefrom gravitally, a pump whose pressure side has a connection with the liquor-receiving portion of the vat for circulating liquor through the latter, and a connection between said heater and the suction side of the pump.

4. A dyeing apparatus comprising a vertical cylindrical vat, an inlet in the bottom of said vat, liquid-distributing means adjacent said inlet, a pump, piping connecting said pump with said inlet and with the overflow of the tank, and heating means interposed in said piping on both sides of said pump.

5. A dyeing apparatus comprising a dye vat, a chamber arranged outside of the dye vat and having connection with the discharge side of the latter, said chamber being provided interiorly with means for causing the liquor to flow circuitously therethrough and having means for heating the liquor, and connections between the discharge side of the heating chamber and dye vat, said connection including a centrifugal pump arranged to force the heated dye liquor under pressure into the dye vat.

6. A dyeing apparatus comprising a dye

vat, a chamber arranged outside the dye vat and having connection with the discharge side of the latter and provided interiorly with a dividing wall which terminates above the bottom of the chamber, heating pipes coiled in said chamber and arranged in the space between the end of the dividing wall and the bottom of the chamber and provided with emission apertures, a centrifugal pump, a connection between said pump and the discharge side of said chamber and a connection between said pump and the liquor-receiving part of the dye vat.

7. In apparatus for cold vat dyeing, the combination with a vat arranged for cold vat dyeing, of a circulating pump, connections between said pump and the upper and lower parts of said vat, and a heater interposed in one of said connections through which the dye liquor passes provided with a perforated steam pipe covering the bottom of the heater and arranged to project a multiplicity of steam jets upward through the contents of the heater whereby to heat said contents and maintain constant circulation throughout said contents.

8. In apparatus for cold vat dyeing, the combination with a vat arranged for cold vat dyeing, of a circulating pump, connections between said pump and spaced portions of said vat and a heater interposed in one of said connections through which the dye liquor passes, said heater being provided with a perforated steam pipe covering the bottom of the heater and arranged to project a multiplicity of steam jets upward through the contents of the heater, the heater being further provided with means to cause the liquor passing therethrough to flow in close relation to said steam pipe.

In testimony whereof I have hereunto set my hand in presence of two subscribing witnesses.

DAVID MORLEY HEY.
